SCREEN AND SCREEN MOUNTING

Mark E. Arenwald and Melvin Arenwald, Miami Beach, Fla., and John W. Flucker, Long Beach, N. Y.

Application August 3, 1949, Serial No. 108,306

3 Claims. (Cl. 160—369)

1

This invention relates to improvements in insect screens and the mounting means therefor in conventional window structures.

It is an object of the present invention to form an insect screen having a frame of extruded metal and guide means for the support of the frame in a conventional window opening having resilient means in both the guide and the frame to permit shifting of the frame to uncover the opening, while the frame is maintained in various degrees of adjustment under the influence of the resilient means.

A further object of the invention resides in the provision of insect screens having a rigid frame of extruded metal adapted to be shifted easily and conveniently to open or closed position and which will remain in the various positions of shifting and metallic spring projected guide devices arranged in the window opening for the sliding reception of the frames, such guides formed of a fixed channel member and an overriding channel member shiftable laterally thereon under the influence of a plurality of springs whereby the fixed and overriding members provide an equalizing guide for the screen frames in those windows having irregular side walls.

It has been found extremely desirable to provide in the conventional double hung windows, screen devices capable of being shifted to an uncovering position to permit an exit through the opening for the exterior cleaning of windows, will always remain in any position of adjustment, may be used either as single screens or as double overlapping screens, readily adjust themselves to overcome irregularities in the window, are light in weight, strong, durable, cheap to manufacture and are highly convenient in use.

Other objects and advantages of the invention will be readily apparent during the course of the following description, reference being had to the accompanying drawings, wherein has been illustrated a preferred form thereof.

In the drawings:

Figure 1 is an outer side elevation of a conventional window, showing the invention in use.

Figure 2 is a vertical section, taken on line 2—2 of Figure 1.

Figure 3 is a fragmentary horizontal section, taken on line 3—3 of Figure 1.

Figure 4 is a fragmentary vertical section taken on line 4—4 of Figure 3.

Figure 5 is a fragmentary perspective view of a corner of one frame member and.

Figure 6 is a perspective view of a friction spring device.

2

Like numerals are employed to designate like parts throughout the several figures of the drawings.

Referring specifically to the drawings, the numeral 5 designates a conventional window of the double hung type, having side rails 6 and top header 7 and sill 8. Window sash 9 are mounted in the usual manner to be raised and lowered in the guides 10, formed by the usual strips 11.

10 Rigidly secured to the inner faces of the side rails 6, in the space normally provided for wood frame screens, are channel members 12, of a height substantially that of the window opening. The channels 12 are held in fixed position 15 against shifting, by screws 13. The screws 13 further serve as mounting means for generally V-shaped leaf springs 14. The terminal ends of the springs are curved, at 15. It is contemplated that any suitable number of the springs 14 may be employed in each channel, although it has been found that a spring adjacent the upper and lower end of the channel and one in the center is sufficient for normal use. Overriding the channel 12, is a channel member 16, having an inside 20 width sufficient to permit a sliding fit over the channel 12. The channel 16 has its outer side wall extended at 17, for its full length and parallel ribs 18, forming identical guide grooves 19, likewise extend for the full length of the channel. 25 The grooves 19 are adapted to slidably receive upper and lower screen frames 20 and 21, to be described. As before pointed out, the channels 16 slidably override the channels 12 and are normally urged outwardly by the engagement of the 30 curved ends 15 of the springs 14, against the inner wall of the channel 16, thus presenting a resilient mounting for the screen frames 20 and 21 throughout the sliding of the frames. The resiliency of the mounting for the channels 16 35 adequately compensates for slight irregularities that might be present in the window frame, providing at all times parallel guides upon opposite sides of the window.

The upper screen frame 20 is formed generally 40 rectangular and comprises parallel sides rails and parallel upper and lower rails 22 and 23. The rails 22 and 23 are preferably extruded light weight metal, such as aluminum and the several rails are mitered at their corners, as at 24. The several rails are provided with a generally rectangular shaped channel 25 throughout their 45 length and the channel 25 communicates with the marginal edge of the frame through the medium of a relatively narrow slot 26, having its edges 50 rounded. The rails are further provided with an

undercut channel 27, for the reception of the marginal edge of the screen cloth 28. The edge of the screen cloth is held against displacement from the channel 27, by a compressible bead 29 that is forced into the channel. The frame is rigidly held in assembled position at the mitered corners, by angle bars 30, crimped or otherwise held in the channel 25 of adjoining frame sections, as clearly shown in Figure 4. The slot of the upper rail 23 may carry a strip therein that projects slightly above the rail to overcome any slight irregularity in the header of the window. This strip is indicated at 31, in Figure 2.

The lower screen frame 21 includes extruded side rails 32, parallel with each other and upper and lower extruded rails 33 and 34. The rails 32 and 33 are identical in shape and are provided with rectangular channels 35, communicating with the marginal edge of the frame, through the medium of the relatively narrow slot 36. Undercut channels 37 are provided for the reception of the marginal edges of the screen cloth 38. The frame members 32 and 33 are identical to the frame members 22 and 23. The lower frame member 34 is formed relatively wider than the frame members 32 and likewise is provided with the channel 35 and the undercut channel 37. An identical slot 36 extends from the channel 35 to the marginal edge of the member 34. A strip 39 is positioned in the slot 36 of the member 34 for engagement with the sill of the window as an equalizer to overcome any irregularities of the sill. The frame 21 is assembled in a manner identical with that of the frame 20, by mitering the corners and rigidly binding them together by the angle bars 30. The frame member 34 is provided with a horizontal lip 40, as a means to facilitate the raising and lowering of the frame. Any suitable locking means, not shown, may be employed for retaining the screen frames in closure position against unauthorized movement.

As clearly shown, the upper and lower frames 20 and 21 are adapted to partake of vertical sliding movement in the guide grooves 19 of the channel 16, with the frame 20 being arranged in the outer groove, while the frame 21 is arranged in the inner groove and, in closed position, the lower rail 23 and the upper rail 33 are in parallel alignment, with the rails spaced a distance equal to the thickness of the ribs 18. The frames 20 and 21 are independently shiftable in their respective grooves 19.

As before pointed out, the springs 14 exert a continuous outward pressure upon the channels 16, which pressure would, under certain favorable conditions, be sufficient to hold the frames 20 and 21 against accidental sliding in the grooves. However, to insure against such accidental sliding, due to jarring or excess weight in larger screens, it has been found desirable to provide additional friction means that will maintain the screen frames in any position of adjustment. For this purpose, a plurality of semi-circular leaf springs 41, having angularly disposed terminal ends 42 of a width that permit of a snug engagement in the channels 25 and 35 of the side rails 22 and 32, and are arranged at predetermined points in the side rails 22 and 32, with the semi-circular leaf projecting through the slots 26 and 36 for frictional engagement with the bottom walls of the grooves 19. The terminal ends 42 are further bent at an abrupt angle, as at 43, so that, when the spring 41 is flexed inwardly, the ends 42 will rock upon the bottom of the channels 25 and 35, causing the ends 43 to bite

against the opposite wall of the channels, thus preventing any tendency of the springs 41 to slip in the channels when the screen frames are moved to open or closed position.

In the use of the device, the channel members 12, having first been installed, with their springs 14, the channels are then positioned thereover. Limit screws 44 are then engaged in suitable openings formed in the side walls of the channels 16 and freely ride in horizontal slots 45, formed in the side walls of the channels 12. Thus, the channels 12 and 16 are yieldably held in mounted position against the sides of the window frame against displacement. The frames 20 and 21 are then mounted in their respective grooves 19 by first engaging one edge of the frame in a groove at one side of the window and, by a sidewise pressure, compressing the springs 14, provides sufficient clearance for the opposite side of the frame to engage in its groove. This method of engagement is identical with both frames and the removal of the frames is done in a similar manner. The combined yieldable pressure of the springs 14 and 41 assures that the screen frames will remain in any position of adjustment, providing an easy vertical shifting of the frames. Further, the yieldable nature of the channels 12 and 16 assures of a perfectly aligned guide for the frames, regardless of the irregularities of the window frame.

While the structure hereinbefore described was designed primarily for insect screens, it will be obvious, that by slight modifications in the frames, a sheet of glass may be substituted for the screen wire, thus providing a very desirable storm window.

It will be apparent from the foregoing, that a very simple and highly efficient window screen has been provided. The parts are few and simple, are easily extruded for economy in manufacture, are rigidly held in assembled relation against twisting by the corner angles, is neat in appearance, readily lends itself to installations upon various types of windows, permits ready access to the outer sides of the window and is simply and easily installed or removed.

It is to be understood, that the invention is not limited to the precise arrangement shown, but that it includes within its purview, whatever changes fairly come within either the terms or the spirit of the appended claims.

Having described our invention, what we claim as new and desire to secure by Letters Patent is:

1. A screen and mounting means therefor in a window opening that comprises a pair of screen frames formed of extruded side, upper and lower rails provided with a peripheral slot therearound and provided with an inner channel communicating with the slot, a plurality of semi-circular friction springs mounted in the slots of the side rails and having enlarged head portions engageable in the channels, the springs projecting beyond the marginal edge of the side frame members, channel members vertically arranged and fixed upon the sides of the window opening in parallel relation, a channel member provided with a pair of spaced guide grooves upon its outer face, said last named channel adapted to override the fixed channel members and movable toward and from the fixed channel member, spring devices between the last named channel members to urge them apart, means for limiting the outward movement of guide carrying channel member, the semi-circular springs of the frame frictionally engaging the bottoms of the

guide grooves and equalizer strips carried by the upper rail of the upper frame and the bottom rail of the lower frame and supported in said slots.

2. Screen and screen mountings for window openings that comprises a pair of rectangular screen frames for vertical sliding movement in a window opening with one frame positioned inwardly of the other for clearance with each other, the frames formed of extruded parallel side rails and extruded parallel top and bottom rails, the frames provided with inner annular undercut channels for the reception of the marginal edges of a sheet of screen wire, a binding strip engageable in the channels for maintaining the wire against displacement, the several rails provided throughout their length with a circumferential slot and an inner channel of greater diameter than the slot and having communication with the slot, the said frames mitered at their corners and rigidly connected, equalizer strips carried in the slots of the upper rail of the upper frame and the lower rail of the lower frame, semi-circular springs having enlarged terminal ends for engagement in the inner channels of the side rails, the semi-circular spring extending through the slots and beyond the outer edge of the side rails, the enlarged terminal ends adapted to grip the walls of the inner channel when the spring is under tension, mounting channels vertically affixed to the sides of the window opening in parallel manner, leaf springs carried within the last named channel and projecting forwardly thereof, a second channel co-extensive in length with the mounting channel and of a width to override the mounting channel in snug engagement and urged outwardly by the leaf springs, ribs formed on the second named channel and equi-distantly spaced to form identical vertical guide grooves for the slidable reception of the frames, stop screws for limiting the outer movement of the guide carrying channel under the influence of the leaf springs, the frames slidable in the grooves and frictionally held in adjusted position by the semi-circular springs.

3. Screen and screen frame mounting for window openings that comprises an upper and lower screen frame vertically offset from each other, said frames formed of parallel side rails and upper and lower parallel rails extruded and mitered at their corners for forming a rectangular frame, the extrusion forming an inner annular undercut channel entirely around the frame for the reception of the marginal edge of a sheet of screen wire, a wedging strip engage-

able in the channel for retaining the wire against displacement, the frames provided with a relatively narrow slot entirely around their circumferential edge, the frame having an enlarged inner channel communicating with the slot, the lower frame having its lower rail formed relatively wider and provided with an integral horizontal lip inwardly extending for the major portion of its length, an equalizer strip arranged in the slot of the lower rail of the lower frame and projecting slightly therebeyond, angle bars rigidly connecting the mitered corners of the frames, a plurality of semi-circular leaf springs carried by the side rails of the frames and operating through the slots and projecting therebeyond, the springs having enlarged angularly disposed heads positioned in the inner channels, the terminal ends of the heads bent at an abrupt angle for gripping action on the side wall of the channels when the springs are under tension, guide means for the vertical movement of the screen frames that comprises fixed channel members secured to the opposite sides of the window opening in vertical parallelism, flat leaf springs arranged in the fixed channels and secured intermediate their ends, with their ends inclined outwardly and curved inwardly at their terminus, a guide channel for overriding engagement with the fixed channels and urged outwardly by the last named springs, means for limiting the outer movement of the guide channels under the influence of the flat leaf spring, equidistantly spaced parallel ribs vertically formed on the guide channel to provide identical outwardly opening guide grooves, the frames adapted to slidably engage in the guide grooves with the semi-circular springs frictionally engaging the bottom of the grooves, the said frames independently slidable in their respective groove and held against accidental slipping by the combined actions of the several springs.
